REFRIGERATOR

Harry L. Merrill, Nashua, N. H.

Application March 25, 1936, Serial No. 70,741

6 Claims. (Cl. 62—46)

My invention relates to refrigerators and particularly to improvements in refrigerators of the front icing type and in which the cold air from the ice compartment flows downwardly into the storage compartment through a centrally disposed opening in the bottom of the partition which divides the interior of the refrigerator into said compartments. At the present time a great quantity of ice sold is manufactured in cakes of standard size and shape, and while my invention is in no sense limited to the use of manufactured ice, because natural ice can be cut more or less to a desired size and shape, I find that in a refrigerator designed to be charged with a standardized cake of ice whereby small clearance especially at the ends is permitted, and wherein the air circulation is controlled and directed in a particular way, it is possible not only to maintain a uniform temperature in the storage compartment several degrees lower than has heretofore been possible but also to attain a substantially flat meltage of the ice. This last feature is extremely desirable not only because it facilitates re-icing but because it permits the re-icing in such a way as to assure continued efficient operation for indefinitely long periods.

Various refrigerators have been designed in which the warm air from the storage compartment is conducted across the bottom of the ice. In such cases it is obvious that the temperature of the circulating air is highest at the point where it first contacts the ice or the metal heat-conducting surfaces in contact therewith. Hence, the ice melts fastest at the point where it contacts the air of highest temperature and, if this point is at one only of the bottom edges, the cake or block soon acquires a tilt or list toward that edge. In order to compensate for this tilting or listing it has been proposed to vary the area of the heat transfer surfaces which the air contacts in passing across the bottom of the ice; these areas being least at the point where the air enters and greatest in the zones where the air is coolest. Designs of this character are not satisfactory because it is impossible properly to proportion the heat conducting areas to conform to all operating conditions.

In my copending applications Serial Nos. 57,673 and 57,674 I have disclosed refrigerators characterized by the appreciably lower temperatures which it is possible to maintain in the storage compartment and by the flat meltage of the ice. The present invention, in a way, combines desirable features found separately in the aforementioned applications and other features whereby the

general design is simplified without sacrificing any of the advantages of the other types.

With these and other objects in view my invention includes the novel elements and the combinations and arrangements thereof described below and illustrated in the accompanying drawing in which—

Fig. 1 is a fragmentary cross section of my refrigerator;

Fig. 2 is a cross section similar to Fig. 1 showing a modification;

Fig. 3 is a plan view of the ice rack; and

Fig. 4 is a front elevation view of the rack.

Referring to the drawing, my refrigerator comprises the usual heat-insulated cabinet 1 provided with a transverse partition therein, represented generally by the numeral 2, which divides the interior of the cabinet into a refrigerant space 3 above and a storage space 4 below. The partition 2 is preferably heat-insulated and comprises a metal covering 5 enclosing heat-insulating material 6. For purposes of clearly illustrating the construction, the thickness of the partition is exaggerated in the drawing. This partition is provided with a central opening 7 for the down flow of cold air.

Supported on the partition with its bottom in closely spaced relation thereto is the ice rack 8 which preferably, but not necessarily, comprises a single piece of thin sheet metal bent to form a plurality of V-shaped ridges and valleys which extend parallel to the sides of the cabinet or, in other words, from the front to the back of the refrigerator so that in re-icing, the edge of a block of ice may be supported thereon and the block pushed easily into the box; it being understood that there is an icing door at the front having its sill at about the level of the top of the rack. Welded or otherwise secured to the bottom of the rack are supports represented generally by the numeral 9. Where the partition 2 is inclined downwardly towards the central opening, as shown in Fig. 1, the supports are in the form shown at 10 so that the top of the ice rack when supported on the partition is substantially horizontal. Where the partition has only a slight drainage inclination towards the central opening, as shown in Fig. 2, the supports for the rack are of the type shown at 11. It is to be understood in either case that the partition is inclined slightly from the front toward a drain pipe 12 at the rear and lips 13 are turned up at the edges of the central opening to prevent water from flowing through the central opening into the storage compartment.

Adjacent the interior sides of the cabinet are upwardly extending ducts 14 for the up-flow of warm air from the storage compartment to the refrigerating compartment. One side of each 5 duct is formed by the side of the cabinet and the other side by an insulated baffle 15 which extends upwardly to the interior top of the cabinet but which is provided with a lateral opening 16 at an elevation slightly above the top of the ice rack; 10 the ducts being closed by deflectors 17 above the lateral openings. The dotted lines 18 represent a block of ice resting upon the rack and, in practice, the warm air issuing from the lateral opening 16 impinges against the lower side portions of 15 the block 18 and undercuts the same as shown at 19. It will be noted that the ice rack at the ends is spaced somewhat from the baffles 15 to provide air passages 20 for the down-flow of air into the 20 passage between the transverse partition and the ice rack.

The warm air issuing from the top of the ducts 14 and impinging against the lower side or end portions of the ice block is sufficiently chilled by its contact with the ice so that it flows downwardly through the spaces 20 into the passage 25 between the ice rack and the partition and thus to the central opening. Moreover, the undercut portions of the ice which, as the melting progresses, form pocket-like cavities, not only prevent the warm air from rising into the upper 30 part of the ice compartment but actually deflect it downwardly concurrently with the chilling thereof.

The ice rack may be open or substantially 35 imperforate but in the latter case it is desirable to provide openings, such as those shown at 21 in Fig. 3, to permit water to drop therethrough and wash the air in the air passage beneath the rack and also to permit air to flow downwardly there- 40 through when the openings become uncovered due to the melting of the ice to a small piece.

In order to prevent condensation on the bottom 45 of the rack from falling through the opening in partition 2 a deflector plate 22 is secured to the bottom of the rack over the central opening. This plate is downwardly inclined from the center and its edges overlie the partition so that water dropping therefrom will fall on the top of the partition instead of falling through the central 50 opening.

The rack supports 9 extend somewhat beyond the rack, as shown at 23 and 24, and serve to space the rack from the front and back of the refrigerator to provide additional spaces here for 55 the downflow of cold air.

Stops 25, are also preferably provided on top of the rack at the rear to prevent the ice cake from being pushed against the interior back of the cabinet.

While I have described my invention in its 60 preferred embodiment, it is to be understood that the words which I have used are words of description rather than of limitation. Hence, changes within the purview of the appended claims may 65 be made without departing from the true scope and spirit of my invention in its broader aspects.

What I claim is:

1. The method of refrigerating with a body of 70 ice whereby to confine the progressive meltage thereof substantially to the lower portions of said body which comprises dividing a flow of air to be cooled into two, separate, substantially equal streams, directing said streams simultaneously into contact with opposite ends of said body in 75 zones near the bottom thereof, whereby to effect

an "undercutting" of said body in said zones and also to effect an initial chilling of the air to increase its density and effect a downward flow of said streams, and thereafter directing the flow of said streams beneath said body of ice to a central 5 zone of confluence while maintaining said flowing streams in high, heat-transfer-relation to the bottom of said ice.

2. Those steps in the method of refrigerating with a body of ice whereby to confine the progressive meltage thereof substantially to the lower portions of said body which comprise supporting the ice at the bottom thereof, simultaneously projecting the air to be cooled at substantially equal rates directly against lower opposite side 10 portions of said body above but adjacent the zones of support thereof; whereby to effect a chilling of the air and an increase in its density to initiate a downward flow thereof at these points; directing the downflowing air streams beneath said body 15 of ice while maintaining said flowing streams in high, heat-transfer-relation to the bottom of said ice, and thereafter combining said streams.

3. An ice refrigerator comprising a cabinet, a transverse partition therein provided with a 25 central opening for the down flow of cold air and dividing the interior of said cabinet into an ice compartment above and a storage compartment below, an ice rack in said ice compartment co-operating with said partition to form air 30 passages therebetween communicating with said central opening and with said ice compartment at opposite sides thereof, means for conducting warm air upwardly from said storage compartment in separate streams at said opposite sides 35 of said compartment and discharging it directly against opposite sides of a body of ice supported on said rack and in zones just above the zones of communication of said air passages with said ice compartment; whereby to effect an undercutting of said ice adjacent said rack and a downward flow of said air streams into said passages through the deflecting effect of said undercuttings thereon combined with the force of gravity due to the increase in density of the air by reason 40 of its contact with said ice.

4. An ice refrigerator comprising a cabinet, a transverse partition therein provided with a central opening for the down flow of cold air and dividing the interior of said cabinet into an ice 50 compartment above and a storage compartment below; said partition being downwardly inclined from the sides thereof towards said opening; an ice rack in said ice compartment co-operating with said partition to form air passages therebetween 55 communicating with said central opening and with said ice compartment at opposite sides thereof, means for conducting warm air upwardly from said storage compartment in separate streams at said opposite sides of said compartment and discharging it directly against opposite sides of a body of ice supported on said rack and in zones just above said rack and above the zones of communication of said air passages with said ice compartment; whereby to effect an undercutting of said ice adjacent said rack and a downward flow of said air streams into said passages through the deflecting effect of said undercuttings thereon combined with the force of gravity 60 due to the increase in density of the air by reason of its contact with said ice.

5. An ice refrigerator comprising a cabinet, a transverse partition therein provided with a central opening for the down flow of cold air and dividing the interior of said cabinet into an ice 65

compartment above and a storage compartment below, an ice rack in said ice compartment comprising thin metal having a plurality of alternate ridges and valleys therein extending in a direction from front to back of said cabinet and cooperating with said partition to form air passages therebetween communicating with said central opening and with said ice compartment at opposite sides thereof, means for conducting warm air upwardly from said storage compartment in separate streams at said opposite sides of said compartment and discharging it directly against opposite sides of a body of ice supported on said rack and in zones just above said rack and above the zones of communication of said air passages with said ice compartment; whereby to effect an undercutting of said ice adjacent said rack and a downward flow of said air streams into said passages through the deflecting effect of said undercuttings thereon combined with the force of gravity due to the increase in density of the air by reason of its contact with said ice.

6. An ice refrigerator comprising a cabinet, a transverse partition therein provided with a central opening for the down flow of cold air and dividing the interior of said cabinet into an ice

compartment above and a storage compartment below; said partition being downwardly inclined from the sides thereof towards said opening; an ice rack in said ice compartment comprising thin metal having a plurality of alternate ridges and valleys therein extending in a direction from front to back of said cabinet and cooperating with said partition to form air passages therebetween communicating with said central opening and with said ice compartment at opposite sides thereof, 10 means for conducting warm air upwardly from said storage compartment in separate streams at said opposite sides of said compartment and discharging it directly against opposite sides of a body of ice supported on said rack and in zones 15 just above said rack and above the zones of communication of said air passages with said ice compartment; whereby to effect an undercutting of said ice adjacent said rack and a downward flow of said air streams into said passages 20 through the deflecting effect of said undercuttings thereon combined with the force of gravity due to the increase in density of the air by reason of its contact with said ice.
